US0D1011090S

(12) **United States Design Patent** (10) Patent No.: **US D1,011,090 S**
(45) Date of Patent: ** Jan. 16, 2024

(54) **MEMORY SPONGE LEG PILLOW**

(71) Applicants: **Hanlei Zhang**, Anhui (CN); **Lijiang Chen**, Zhejiang (CN)

(72) Inventors: **Hanlei Zhang**, Anhui (CN); **Lijiang Chen**, Zhejiang (CN)

(**) Term: **15 Years**

(21) Appl. No.: **29/899,667**

(22) Filed: **Aug. 11, 2023**

(51) LOC (14) Cl. **06-09**

(52) U.S. Cl.

USPC **D6/601**

(58) **Field of Classification Search**

(57) **CLAIM**

The ornamental design for a memory sponge leg pillow, as shown and described.

DESCRIPTION

FIG. 1 is a perspective view of the memory sponge leg pillow showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures illustrate portions of the memory sponge leg pillow that form no part of the claimed design.

1 Claim, 7 Drawing Sheets
